UNITED STATES PATENT OFFICE.

ALFRED C. REX, OF PHILADELPHIA, PENNSYLVANIA.

DESIGN FOR A BOX.

SPECIFICATION forming part of Design No. 17,394, dated June 14, 1887.

Application filed April 15, 1887. Serial No. 234,976. Term of patent 3½ years.

To all whom it may concern:

Be it known that I, ALFRED C. REX, a citizen of the United States, and a resident of Philadelphia, Pennsylvania, have invented a new and useful Design for a Box for Small Articles, of which the following is a specification.

My design for a box for coins, matches, or various other articles is fully illustrated in the accompanying drawing, the view in which is in perspective. The base of the box is in the representation of a camel resting on its haunches, and located centrally upon its back is a representation of a treasure-chest. The interior of this chest is in the form of a box.

I claim--

The herein described design for a box, consisting of the representation of a camel resting on its haunches, with a treasure-chest located centrally upon its back, substantially as shown and described.

In testimony whereof I have signed my name to this specification in the presence of two subscribing witnesses.

ALFRED C. REX.
